UNITED STATES PATENT OFFICE

172,935

FISHERMAN'S KNIFE

Floyd Oles, Tacoma, Wash.

Application February 1, 1954, Serial No. 28,775

Term of patent 7 years

(Cl. D22—3)

To all whom it may concern:

Be it known that I, Floyd Oles, a citizen of the United States, resident of Tacoma, Pierce County, Washington, have invented a new, original, and ornamental Design for a Fisherman's Knife, of which the following is a specification, reference being had to the accompanying drawing, forming a part hereof.

Figure 1 is a side elevational view of a fisherman's knife illustrating my new design,

Figure 2 is a bottom plan view, and

Figure 3 is a butt end view thereof.

I claim:

The ornamental design for a fisherman's knife, substantially as shown.
